(57) **CLAIM**

The ornamental design for a combined rail member and connector, as shown and described.

DESCRIPTION

FIG. 1 is a perspective view of a combined rail member and connector showing our new design;

FIG. 2 is both a left end view and a right end view thereof;
FIG. 3 is both a reduced front end view and a rear end view thereof;

FIG. 4 is a reduced top plan view thereof;

FIG. 5 is a reduced top plan view thereof;

FIG. 6 is an enlarged perspective view the connector removed from the rail member;

FIG. 7 is an enlarged perspective view of the connector member being inserted onto an end of a rail member; and,
FIG. 8 is a reduced perspective view of a plurality of rail members with connectors integrated with one another.

The connector is shown away from the pallet component in FIG. 5 for convenience of illustration.

The pallet component is partially shown in FIG. 6 for convenience of illustration.

The broken lines shown in FIG. 7 are for illustrative purposes only and form no part of the claimed design.

The broken line showing of a platform in FIG. 8 is for illustrative purposes only and forms no part of the claimed design.
